F. W. ADLOF,
DRYING APPARATUS.
APPLICATION FILED MAR. 1, 1916.

1,194,118.

Patented Aug. 8, 1916.

UNITED STATES PATENT OFFICE.

FREDERICK W. ADLOF, OF NEW BRIGHTON, PENNSYLVANIA.

DRYING APPARATUS.

1,194,118.

Specification of Letters Patent. Patented Aug. 8, 1916.

Application filed March 1, 1916. Serial No. 81,373.

To all whom it may concern:

Be it known that I, FREDERICK W. ADLOF, a citizen of the United States, and a resident of New Brighton, in the county of Beaver and State of Pennsylvania, have invented a new and Improved Drying Apparatus, of which the following is a full, clear, and exact description.

This invention relates to an apparatus for drying grain, sand or other granular material, and the apparatus is of that type in which the material flows by gravity down a columnar structure or stack through which hot air or fire gases travel for evaporating the moisture from the material to be dried.

The invention has for its general objects to improve and simplify the construction and operation of apparatus of the character referred to so as to be reliable and efficient in use, comparatively simple and inexpensive to manufacture and keep in operative condition, and so designed as to have a large capacity in a relatively small space.

A more specific object of the invention is the provision of a drying apparatus having a novel arrangement of passages or ducts for the material to be dried and for the products of combustion from the drying furnace, whereby the material is kept out of contact with the fire gases, which is especially desirable for the drying of grains and the like.

More in detail the invention has for its objects to provide a drying apparatus composed of three tubes or stacks arranged concentrically one within the other, the space between the inner and intermediate stack being divided by helical flanges into alternate fire flues and drying ducts, whereby the material is effectively acted on by heat from all points, since the fire gases pass upwardly through the inner tube or stack, downwardly through the spiral passages alternating with the passages for the material to be dried, and upwardly through the space between the outer and intermediate stacks, and in connection with such structure, means will be provided for regulating the feeding of the material to be dried and the draft through the fire gas conduit.

With such objects in view, and others which will appear as the description proceeds, the invention comprises various novel features of construction and arrangement of parts which will be set forth with par-

ticularity in the following description and claims appended hereto.

In the accompanying drawings, which illustrate one embodiment of the invention and wherein similar characters of reference indicate corresponding parts in all the views, Figure 1 is a vertical section of the apparatus with portions in elevation; Fig. 2 is a plan view on the line 2—2, Fig. 1; and Figs. 3 to 6 inclusive are transverse sections respectively on the line 3—3, 4—4, 5—5 and 6—6, Fig. 1.

Referring to the drawing, 1 designates a furnace of any approved construction which forms the supporting base for the stacks or tubes 2, 3 and 4 which are arranged concentrically one within the other and are vertical. These stacks are preferably made of sections connected end to end, whereby the total height of the apparatus may be varied to suit requirements. The inner tube or stack 2 is in open communication with the fire chamber *a* of the furnace 1, and the fire gases freely ascend to the top of the stack 2, which is formed into an enlargement 5 surmounted by a conical hood or deflector 6, there being openings 7 at opposite sides in the head or enlargement 5 for permitting the fire gases to pass out of the inner stack. The space between the inner and intermediate stacks or tubes 2 and 3 is divided into a plurality of passages 8 and 9 separated by helical flanges or ribs 10, the passages 8 being in communication with the respective openings 7, whereby the fire gases will flow downwardly through the passages 8 to the bottom of the apparatus and pass through openings 11 in the intermediate tube 3 to the space or flue 12 lying between the outer and intermediate stacks, such space being in free open communication to the atmosphere at the top 13. It will thus be seen that the fire gases in transit from the furnace 1 to the atmosphere flow first upwardly in a straight line, dividing at the top, and flowing downwardly in helical vertical courses in the passages 8, and thence upwardly through the passage 12. The ducts or passages 9 are wholly out of communication with the passages 8 for the fire gases, but the walls of the passages 9 formed by portions of the inner and intermediate tubes or stacks 2 and 3 and by the flanges 10, are all in contact with hot fire gases, so that the material flowing down the helical passages 9 will be effectively heated and the

105
106
110

moisture evaporated therefrom. The lower ends of the passages 9 terminate in spouts 14 which extend out through the outer stack for the discharge of the dried material.

5 The material is fed into the contracted mouth 15 on the top of the intermediate stack and surrounding the conical deflector 6. A screen 16 is provided in the mouth section 15, and under the screen are slide 10 valves 17 for regulating the flow of the material down the passages 9. Over the openings 7 of the inner stack are flanges 18 for preventing the material from passing into the openings and guiding the material into 15 the passages 9. For regulating the heat a damper 19 is arranged in the upper end of the inner stack 2. To facilitate the extraction of the vapor an outlet pipe 20 is provided within the outermost stack 4, and 20 this pipe has connections 21 with the passages 9 at different points, and the bottom of the pipe is provided with a valve 22 from which the vapor may be drawn off.

From the foregoing description taken in 25 connection with the accompanying drawings, the advantages of the construction and method of operation will be readily understood by those skilled in the art to which the invention appertains, and while I have described the principle of operation, together 30 with the apparatus which I now consider to be the best embodiment thereof, I desire to have it understood that the apparatus shown is merely illustrative and that such changes 35 may be made when desired as fall within the scope of the appended claims.

Having thus described my invention, I claim as new and desire to secure by Letters Patent:

40 1. A drying apparatus comprising three concentric tubes, means for supplying fire gases to the bottom of the inner tube, helical flanges between the inner and intermediate tubes dividing the space into alternate helical heating and drying passages, said heating 45 passages having their upper ends communicating with the top of the inner tube to receive the fire gases therefrom, means for supplying to the upper end of the drying 50 passages the material to be dried, and means for conducting the fire gases from the heating passages to the bottom of the outer tube, the outer tube having its upper end open to the atmosphere.

55 2. A drying apparatus comprising a fur-

nace, a central vertical tube in open communication at its bottom with the furnace, a deflector closing the upper end of the tube and having lateral openings, a tube surrounding the first-mentioned tube, flanges 60 intermediate the tubes for dividing the space into separate passages, certain of the passages communicating with the inner tube through the said openings, a mouth on the upper end of the second tube for receiving 65 the material to be dried, and in communication with the other of the said passages, valve means for controlling the feed of the material from the mouth to the communicating passages, a third tube surrounding the 70 second-mentioned tube to form a passage open to the atmosphere at its top and communicating with the passages that communicate with the inner tube, and an outlet means passing out of the bottom of the outer 75 tube for the discharge of the material after being dried.

3. A drying apparatus comprising a furnace, a structure having separate portions through which fire gases from the furnace 80 pass upwardly to a given point and thence downwardly and thence upwardly to escape to the atmosphere, and a plurality of material-drying ducts disposed in that portion of the structure down which the fire gases 85 flow, said ducts being heated throughout their length and entirely around the sides thereof.

4. A drying apparatus comprising a furnace, a structure having separate portions through which fire gases from the furnace pass upwardly to a given point and thence downwardly and thence upwardly to escape to the atmosphere, a plurality of material-drying ducts disposed in that portion of the 90 structure down which the fire gases flow, said ducts being heated throughout their length and entirely around the sides thereof, means for regulating the feed of the material to the said ducts, means for controlling 95 the draft through the said structure, and means for drawing off the evaporation from the material passing through the ducts.

In testimony whereof I have signed my name to this specification in the presence 105 of two subscribing witnesses.

FREDERICK W. ADLOF.
